(57) **CLAIM**

The ornamental design for an endodontic file clip for an apex locator, as shown and described.

DESCRIPTION

FIG. 1 is a perspective view of an endodontic file clip for an apex locator of the present invention;

FIG. 2 is a rear plan view of the dental implant shown in FIG. 1;

FIG. 3 is a front plan view of the dental implant shown in FIG. 1;

FIG. 4 is a right side view of the dental implant shown in FIG. 1;

FIG. 5 is a left side view of the dental implant shown in FIG. 1;

FIG. 6 is a top view of the dental implant shown in FIG. 1; and,

FIG. 7 is a bottom view of the dental implant shown in FIG. 1.

The broken lines immediately adjacent the claimed areas represent the bounds of the claim, and all other broken lines are included for the purpose of illustrating portions of the dental implant that form no part of the claimed design.
